United States Patent Office

Des. 228,346
Patented Sept. 11, 1973

228,346

AUTOMATIC PIPETTING AND ANALYSIS UNIT

Alfred M. Blumenfeld, Melrose Park, Pa., assignor to
Micromedic Systems, Inc., Philadelphia, Pa.

Filed Sept. 20, 1971, Ser. No. 182,304

Term of patent 14 years

Int. Cl. D16—02

U.S. Cl. D16—2 C

FIG. 1

FIG. 2

FIG. 3

FIG. 5

FIG. 4

FIG. 1 is a front perspective view of an automatic pipetting and analysis unit showing my new design;

FIG. 2 is a front elevational view thereof;

FIG. 3 is a rear elevational view thereof;

FIG. 4 is a top plan view thereof; and

FIG. 5 is a right side elevational view thereof.

I claim:

The ornamental design for an automatic pipetting and analysis unit, substantially as shown and described.
